UNITED STATES PATENT OFFICE.

ALBERT C. LUDLUM, OF NEW YORK, N. Y., AND ARTHUR LOWY, OF NEWARK, NEW JERSEY, ASSIGNEES TO NEW YORK ENGINEERING COMPANY, A CORPORATION OF NEW YORK.

GOLD-DREDGE.

1,315,228.

Specification of Letters Patent.

Patented Sept. 9, 1919.

Application filed March 20, 1916. Serial No. 85,281.

To all whom it may concern:

Be it known that we, ALBERT C. LUDLUM and ARTHUR LOWY, citizens of the United States, residing at New York, in the county 5 of New York and State of New York, and Newark, in the county of Essex and State of New Jersey, respectively, have invented certain new and useful Improvements in Gold-Dredges, of which the following is a 10 full, clear, and exact specification.

This invention relates to improvements in gold dredges and has especial reference to the provision of means for discharging clay and other analogous materials which may be 15 taken up by the dredging buckets independently of the screen and the gold saving tables.

The object of this invention is to provide a system of controlling gates and clay conveyors leading therefrom whereby materials which it is not desired to pass through the screen or over the tables can be rapidly handled and discharged independently of both the screen and the gold saving tables. Not 20 only can such materials be handled more quickly by means of this invention, but no time is lost when pay dirt is reached in changing the delivery so that none of the values will be lost. The dredge buckets discharge into a vertically disposed hopper, the lower end of which discharges into the interior of the screen. Intermediately connected to the hopper is a gravity clay chute which is controlled by a vertically swinging gate 25 which, when in vertical position, leaves the discharge to the screen clear, and when in a horizontal position obstructs the hopper and discharges the clay or other unworkable material into the gravity clay chute, which 30 thence discharges into one or more clay conveyors. Preferably, a plurality of clay conveyors are provided leading from a single chute, and controlled by a swinging gate or switch so as to permit of being used alternately in order to spread the discharged material over a wide area astern of the hull. 35

A further feature of the invention consists in combining with the clay chute which leads to the clay sluices a water nozzle which is 40 specially constructed to discharge a flat stream of water under pressure on the bottom of the chute so that material falling thereon from the digger will be flushed downward and carried away without splash-

ing over the adjacent parts of the machinery. Previous attempts to rapidly dispose of clay by means of water jets have been objectionable and unsatisfactory, because the force of the water was such as to splash muddy water over other parts of the dredge, necessitating additional labor in order to enable the parts to properly operate. 55 60

By the present invention, large quantities of clay and similar objectionable materials can be handled without obstructing the 65 screen and gold saving tables, and the discharges of clay, gangue and tailings can be more easily distributed astern of the dredge.

In the accompanying drawings,

Figures 1 and 2 are elevations of a dredge 70 embodying the invention;

Fig. 3 is a plan view;

Fig. 4 is a detail view on an enlarged scale, and

Fig. 5 is a plan view of part of Fig. 4. 75

1 represents a float or hull carrying a ladder frame 2 on which is an endless chain of buckets 3 running over a wheel 4 at the bottom and a wheel 5 at the top, the wheel 5 being carried by shaft 6. The power is furnished by a steam boiler 7 which operates a turbine 8 which is directly coupled to drive a generator 9. 10 is a condenser, 11 a winch for lifting the ladder driven by auxiliary motor 12, 13 is a high pressure pump driven by auxiliary motor 14, the pump discharge being by pipe 15 to the condenser to pipe 17 and also by pipe 18 to a perforated pipe 19 inside the rotary screen 20. The screen 20 is shown in Fig. 4 and consists of an inclined 85 cylinder carrying external bearings 21 riding on rollers 22, and perforated so as to pass the fine dirt and the values through to the gold tables 23 and sluices 24. The 90 sluices 24 discharge into tail sluices 25 in the usual manner. The gangue or coarse tailings is discharged from the lower end of the screen 20 on to a stacker 27, which conveys it upwardly and discharges sufficiently 95 far from the float to prevent interference. 100

The material from the buckets 3 falls out by gravity as they pass around the wheel 5, and falls down through a hopper 28 on to the inclined bottom 29, and thence by slide 30 into the upper end of screen 20. 105 Any material that passes through the hopper to slide 30 must necessarily go through the screen, passing through the meshes on

to the tables if fine enough, and if not, passing out through the lower end on to the stacker 27. In order to enable the clay to be more quickly disposed of, the hopper 28 is provided with a horizontally pivoted vertically swinging gate 35 pivoted at 36 to the side of the hopper and operated through segment 37 and gear 38 from hand wheel 39. The gate 35 swings downward until stopped in an inclined position by abutments 40, at which position it forms an apron which discharges the material into the inclined trough conveyer 42, from which the material passes to branch trough conveyers 43, 43. The conveyer 42, the gate 35, the nozzle 47, the gate 44, and the branch trough conveyers 43, are all disposed above the upper side of screen 20, so that the conveyers 42 and 43 of simple trough form enable large quantities of materials either wet or dry to be handled and discharged by gravity without requiring additional lifting power, or attention. The chain bucket digger may at times bring up water or mud, as well as comparatively dry solid material, and it is more economical and simple to dispose of all such materials by gravity flow directly overboard through the trough conveyers 43 rather than through the tail sluices from the tables, or by additional pumps or lifting conveyers below the screen and tables. 44 is a swinging gate or switch which in one position cuts off one branch conveyer and in the other position cuts off the other, so that the clay can be distributed behind the dredge and on either side so as not to accumulate in one place and obstruct its movement. When the gate 35 is in vertical position it completes the vertical wall of the hopper above the screen and prevents escape of the valuable containing material.

The clay as discharged by the buckets 3 does not flow very easily, and in order to remove the clay quickly a novel arrangement of water flushing is provided. Branching from the pipe 18 is a water pipe 46, which leads to a horizontal flat or elongated nozzle aperture 47 formed in a casting 48 extending across the bottom of the conveyer 42 immediately in front of the pivot 36 and gate 35. A series of horizontal jets similarly discharging could be used. This nozzle 47 discharges a flat sheet of water under pressure along the bottom of the conveyer 42, so that the clay slides or falls down the incline of gate 35 over the mouth of the nozzle and is flushed away down conveyer 43 by the force of the water. Owing to the water being discharged along the bottom of the conveyer in the same direction as the clay there is little or no splashing, and the clay is prevented from adhering or clogging the conveyers. By this arrangement, it is possible to handle a

much larger volume of unworkable material in a given time, and after the pay dirt is reached no time is lost in cleaning the screen, tables, etc. The specific details and constructions of parts are shown herein by way of illustration only, and various modifications and changes in the form and location may be made without departing from the scope of the appended claims.

Having thus described our invention, we declare that what we claim as new and desire to secure by Letters Patent, is:

1. The combination in a gold dredge with a digger discharging by gravity at the top of the lift, of a hopper below the top of the digger receiving the discharged material and having a fixed inclined bottom to discharge the material into an inclined screen, an inclined screen directly receiving the material discharged from the bottom of the hopper, saving tables below the screen, a down conveyer above and generally parallel to the bottom of the screen and discharging independently of the screen and the tables, a discharge opening through the side of the hopper to said down conveyer, and a gate pivoted on the side of said hopper below said opening and above said fixed bottom discharge and movable inwardly from a vertical position closing access of material to said down conveyer to an inclined position across the hopper to discharge material directly from the digger to said conveyer and cutting off material from the hopper bottom discharge into said screen.

2. The combination in a gold dredge with a chain bucket digger discharging by gravity at the top of the lift, of a hopper below the top of the digger receiving the discharged material and having a fixed inclined bottom to discharge the material into an inclined rotary screen, an inclined rotary screen directly receiving the material discharged from the bottom of the hopper, saving tables below the screen, a down trough conveyer above and generally parallel to the bottom of the screen and discharging independently of the screen and the tables, a discharge opening through the side of the hopper to said down conveyer, means for discharging water under pressure down the bottom of said trough conveyer for preventing adherence of clayey material thereto and accelerating the flow, and a gate pivoted on the side of said hopper below said opening and above said fixed bottom discharge and movable inwardly from a vertical position closing access of material to said down conveyer to an inclined position across the hopper to discharge material directly from the digger to said conveyer and cutting off material from the hopper bottom discharge into said screen.

3. In a gold dredge embodying a digger for lifting the material and a screen and sav-

ing tables below the top of the digger lift fed thereby by gravity, a down trough conveyer between the screen and the digger controlled by a movable gate diverting waste material thereto before it falls into the screen, and a flat downwardly directed water nozzle adjacent the upper end of the trough conveyer for discharging a flat sheet

of water under pressure down along the bottom of the conveyer for preventing adherence of clayey material thereto and accelerating the flow. 10

In testimony whereof we affix our signatures.

ALBERT C. LUDLUM.
ARTHUR LOWY.
